UNITED STATES PATENT OFFICE.

HARRY W. BUTTERWORTH, OF PHILADELPHIA, PENNSYLVANIA, ASSIGNOR
TO THE H. W. BUTTERWORTH & SONS COMPANY, OF PENNSYLVANIA.

AUTOMATIC CLAMP FOR CLOTH-STRETCHING MACHINES.

SPECIFICATION forming part of Letters Patent No. 571,105, dated November 10, 1896.

Application filed June 8, 1896. Serial No. 594,696. (No model.)

To all whom it may concern:

Be it known that I, HARRY W. BUTTERWORTH, of the city and county of Philadelphia, State of Pennsylvania, have invented
5 an Improvement in Automatic Clamps for Textile Machinery, of which the following is a specification.

My invention has reference to automatic clamps for textile machinery; and it consists
10 of certain improvements which are fully set forth in the following specification, and shown in the accompanying drawings, which form a part thereof.

My improvements comprehend certain constructions of a clamp adapted to textile-machines, and especially to tentering-machines, which shall have capacity for a portion thereof being turned out of the way to permit the ready passage of the fabric into the clamp
15 20 and then automatically adjust itself for the proper gripping or clamping of the edge of the fabric.

The special application of my improvements to tentering-machines will make the
25 advantageous features of my improvements more apparent. In tentering-machines the edges of the fabric have heretofore been inserted by hand. The clamps as heretofore made have been impractical to permit the
30 fabric to be inserted automatically within the grasp of the clamp, because the upper jaw of the clamp cannot secure a position above the fabric in passing about the end cylinders of the machine. By my improvements I support the gripping-jaws of the clamps in a movable manner on the frame carried by the chain or link of the conveyer in such a manner that the upper jaw may be turned out of the way when passing about the ends of the tentering-
35 machine where the fabric is delivered to and received from the machine. In this manner the upper gripping-jaw is not in a position to interfere with the passage of the clamps, but may be thrown into and out of operative position at the proper time by stops or cams, so that the device may be automatic. The cams, however, would be arranged to suit the particular machine or machines to which my improved clamp may be applied. By the construction hereinafter set out I provide the lower jaw and the frame for carrying the up-

per jaw in one rigid **U**-shaped structure, so that there is no possibility of the upper jaw failing to act in a positive manner with the lower jaw. Furthermore, by this construction I am enabled to simplify and cheapen the cost of manufacture of adjustable clamps of this character.

The details of my invention will be better understood by reference to the accompanying drawings, in which—

Figure 1 is a plan view of a cloth-clamp embodying my improvements. Fig. 2 is a side elevation thereof. Figs. 3 and 4 are perspective views of the upper jaw and controlling finger for regulating the time of action of the gripping-jaws. Fig. 5 is a side elevation of one end of a tentering-machine, and Fig. 6 is an end elevation of a portion of same.

A is one of the longitudinal main frames of a tentering-machine, and is provided with a conveyer A' made up of links or otherwise guided in a suitable guide B'. The conveyer is guided about guiding rolls or cylinders D' D'. The conveyers are provided with cloth-clamps E', attached to the links thereof and constructed as hereinafter described, and while in Figs. 5 and 6 are shown only upon a few links they may be upon every link or every other link, as desired. The frames of the machine are provided with cams F' for actuating the cloth-clamps.

A' represents a link of the conveyer-chain and is provided with a laterally-projecting frame B, to which the clamp as an entirety is pivoted at D parallel to the length of the conveyer or chain. The conveyer may be formed in any other manner if desired, but commonly is in the form of a sprocket-chain. This part, however, is immaterial to the special construction of my improvements, since the frame B may be attached to any conveyer.

C is a **U**-shaped frame having one of its legs pivoted at D to the laterally-projecting frame B, the latter being open in its middle to permit the frame C to revolve about its axis D, so as to present the open part thereof upward. When the said frame C is raised, as indicated in Fig. 2, a spring K snaps into a recess L and holds it normally in said position. When, however, the frame C is depressed, the spring K is received in a recess

W to normally hold the frame C in the last-named position while on its return through the machine and avoid its swinging. As the conveyer moves the clamp over its course the 5 cam F' or any other suitable cam is employed to act upon the projection M to cause the said frame C to be raised or lowered and move about the pivot D. The lower leg of the frame C constitutes the lower jaw F of the clamp, and when this is in normal clamping position it rests upon an extension E of the frame B, so that it cannot turn farther by the action of the cloth or fabric under the tension or stretching operation. The part E 10 acts as a limit-stop. The jaw G is the upper or movable jaw of the clamp and is pivoted at g to the other leg of the frame C. It is so arranged that by gravity it will fall toward the jaw F, so as to exert a cam action in gripping the fabric.

H is a controlling-finger, which is pivoted upon the same pin g as the upper jaw G and is provided with an upward extension I and lateral arms h. The lateral arms h act upon 25 the jaw G, so that as the arm I is pressed outward under the influence of a suitable cam the jaw G is thrown backward and raised clear of the clamping-jaw F.

The controlling-finger II in practice moves 30 through a vertical aperture J in the floor of the frame C and is in operation held from descending by the cloth upon which it rests. As the cloth or fabric is drawn outward under the said finger H and jaw G it ultimately 35 liberates the finger II, permitting it to fall, and this action causes the clamp G to be liberated, so that it moves toward the jaw F and grips the extreme edge of the fabric. The finger II, therefore, insures the gripping 40 of the fabric very close to its lateral edge or selvage. By this construction it is evident that no action on the part of the fabric can displace the pivot g relatively to the jaw F, and therefore the clamp as an entirety may 45 be constructed with absolute accuracy and yet be provided with means whereby it may be turned into and out of position for the purpose of clamping cloth or permitting its passage by the edge of the cloth when it is being 50 delivered or removed from the machine.

I do not confine myself to any specific details of construction; but my invention comprehends, broadly, a laterally-projecting arm or frame adapted to be moved by a suitable 55 conveyer, combined with the cloth-clamp pivoted to the end thereof and adapted to be turned into or out of operative position thereon as an entirety.

What I claim as new, and desire to secure 60 by Letters Patent, is—

1. In a clamp for textile machinery, a laterally-projecting arm or frame adapted to project from a suitable conveyer, in combination with a cloth-clamp having two jaws pivoted as an entirety thereto and adapted to be moved about a longitudinal axis.

2. In a clamp for textile machinery, a lat-

erally-projecting arm or frame adapted to project from a suitable conveyer, in combination with a cloth-clamp having a stationary 70 jaw and a movable jaw pivoted thereto and adapted to be moved about a longitudinal axis, whereby the pivot of the movable jaw always remains at a fixed distance from the stationary jaw, means for limiting the movement of the clamp as an entirety in one direction, and a spring to hold the clamp as an entirety in operative position when acting upon the cloth.

3. In a clamp for textile machinery, a laterally-projecting arm or frame adapted to project from a suitable conveyer, in combination with a U-shaped frame having one leg thereof pivoted to the laterally-projecting frame and constituting one jaw of a cloth-clamp, and a movable jaw pivoted to the other leg 85 of the U-shaped frame and movable to or from the other jaw.

4. In a clamp for textile machinery, a laterally-projecting arm or frame adapted to project from a suitable conveyer, in combination with a U-shaped frame having one leg thereof pivoted to the laterally-projecting frame and constituting one jaw of a cloth-clamp, a movable jaw pivoted to the other leg 90 of the U-shaped frame and movable to or from the other jaw, and a controlling-finger arranged at the rear of the movable jaw and carried by the U-shaped frame for holding the movable jaw out of gripping action until 95 the proper moment.

5. In a clamp for textile machinery, a laterally-projecting arm or frame adapted to project from a suitable conveyer, in combination with a U-shaped frame having one leg 100 thereof pivoted to the laterally-projecting frame and constituting one jaw of a cloth-clamp, a movable jaw pivoted to the other leg of the U-shaped frame and movable to or from the other jaw, a controlling-finger arranged 105 at the rear of the movable jaw and carried by U-shaped frame for holding the movable jaw out of gripping action until the proper moment, and projections extending from the U-shaped frame and the controlling-finger 110 adapted to be operated upon by suitable cams for imparting movement to these parts at definite times.

6. In a cloth-clamp, a laterally-projecting frame adapted to be attached to and moved 115 by a suitable conveyer, in combination with a cloth-clamp proper comprising a fixed jaw and a movable jaw pivoted in a fixed bearing relatively to the fixed jaw, and a movable connection between the said clamp and the 120 laterally-projecting frame whereby the clamp may be moved as an entirety upon the said frame so as to be capable of being thrown into or out of operative position.

7. In a cloth-clamp, a laterally-projecting 125 frame adapted to be attached to and moved by a suitable conveyer, in combination with a cloth-clamp proper comprising a fixed jaw and a movable jaw pivoted in a fixed bearing

relatively to the fixed jaw, and a movable connection between the said clamp and the laterally-projecting frame whereby the clamp may be moved as an entirety upon the said frame so as to be capable of being thrown into or out of operative position, means for limiting the movement of the clamp proper, and a projection upon the clamp adapted to be actuated for the purpose of moving the clamp upon the laterally-projecting frame.

8. In a cloth-clamp, a laterally-projecting frame adapted to be attached to and moved by a suitable conveyer, in combination with a cloth-clamp proper comprising a fixed jaw and a movable jaw pivoted in a fixed bearing relatively to the fixed jaw, a movable controlling-finger also pivoted upon a fixed axis relatively to the fixed jaw and adapted to sustain the movable jaw out of gripping action relatively to the fixed jaw by resting upon the cloth, and a movable connection between

the said clamp and the laterally-projecting frame whereby the clamp may be moved as an entirety upon the said frame so as to be capable of being thrown into or out of operative position.

9. In a cloth-clamp the combination with the lateral frame B, the pivoted frame C having the fixed jaw F and jointed to the frame B at D, the pivoted gripping-jaw G pivoted at g to the frame C at a fixed distance from the jaw F and a controlling-finger H for holding the movable jaw G out of action when the cloth is arranged under both the jaw G and controlling-finger H.

In testimony of which invention I have hereunto set my hand.

HARRY W. BUTTERWORTH.
